UNITED STATES PATENT OFFICE.

CHARLES R. CRANDLEMERE, OF AMHERST, MASSACHUSETTS.

SQUARE.

Application filed November 5, 1925. Serial No. 67,054.

This invention relates to improvements in squares for use by carpenters in laying out the various component parts of a roof and has as its general object to provide a square which will greatly facilitate this work and permit of laying out of the rafters without any mathematical calculations being required on the part of the carpenter, so that the work may be more accurately carried out and in a more expeditious manner.

The invention has as another object to provide a square embodying indicia upon its opposite faces indicating the number of inches the longest jack rafters are shorter than the common rafters, in accordance with the rise of the roof, the distance the rafters are spaced apart, the side cuts for octagon hip rafters and for octagon jack rafters, the side cuts for hip or valleys rafters and for hip or valley jack rafters, the difference in length in studding in the gables, etc.

The present application is a continuation in part of my prior application filed February 3, 1925, Serial No. 6,564.

25 In the accompanying drawings:

Figure 1 is a plan view of one side of the square embodying the invention.

Figure 2 is a similar view of the opposite side of the square.

30 Figure 3 is a plan view illustrating the manner in which the blade and the arm of the square may be brought to lie parallel to each other, when the square is not in use.

Figure 4 is a fragmentary plan view of one 35 member of the square, illustrating one section of the joint between the blade and the arm.

Figure 5 is a sectional view taken substantially on the line 5—5 of Figure 3.

40 Figures 6, 7 and 8 are views illustrating one method of using the square in laying out and cutting a rafter.

The blade of the square is indicated by the numeral 1 and the arm of the square by the 45 numeral 2. The blade 1 is preferably provided with a lateral extension 3 at one end having a semi-circular end edge 4 terminating at one side in a shoulder 5. The arm 2 is provided with a lateral substantially circular extension 6 and with a shoulder 7 located at the outer side thereof. The extension 6

is formed with a series of lugs indicated by the numeral 8, spaced at an angle of ninety degrees from one another, and the extension 3 is provided upon one face with a series of recesses 9 to accommodate the said lugs 8, a pivot pin or screw 10 being fitted through an opening in the extension 3 and threaded into an opening in the extension 6 and constituting means for connecting the two members 60 of the square in assembled relation, it being evident by reference to Figures 1, 2 and 3 of the drawings, that the blade and arm may be assembled so as to extend at right angles to each other, or these parts may be taken 65 down and adjusted to the position shown in Figure 3, in which position they will extend parallel to and beside each other, and in either case be held in the respective position of adjustment through the medium of the pivot 70 screw 10. Of course, if desired, the lugs 8 and recesses 9 might be dispensed with and the square blade and arm permitted to freely pivot.

A linear scale 11 is provided upon one face 75 of the blade 1 of the square and represents inches and fractions of inches, and extends from one end of the blade to the other end thereof. A similar scale 12 is provided along the outer edge of the arm 2 and extends from 80 one end of said blade to the other end thereof. In like manner, a linear scale representing inches and fractions of inches, and indicated by the numeral 13, is provided upon the said face of the blade 1 and extends 85 along the inner edge of the blade from the inner end thereof to the outer end, and a corresponding linear scale 14 is provided upon the said face of the arm 2 and likewise extends from the inner end of the inner edge of 90 said arm to the outer end of said edge. It will be observed by reference to Figure 1, that the scale marks defining the inch divisions of the linear scale 11 are extended transversely of the blade of the square to a line 15 which extends parallel to the inner edge of the said blade so as to define a longitudinal series of divisions upon this face of the blade. Other parallel lines are indicated upon the said face of the blade so as to define longitudinal spaces indicated by the numerals 16, 17, 18, 19 and 20. At inter- 95 100

vals in the space 16 and at the points of location of certain of the division lines referred to, there are numeral designations 21 indicating side cuts for octagon hip rafters, 5 and at corresponding points in the length of the space 17 there are other numeral designations 22 indicating the side cuts for octagon jack rafters. At the outer end portion of the blade 1 and upon the base thereof above 10 referred to, and in alinement with the longitudinal space 18, there is provided matter reading "Figures in this line are the distance rafters are spaced on centers," and between two of the division lines and in said longitudinal space 18 and opposite the legend above quoted, there is the word "Spacing" indicated by the numeral 24, this word occurring several times in the length of the space 18 and the ordinals "12, 16, 18, and 24" appearing between each two of the said word "Spacing" and indicating the distance at which the jack and common rafters are to be spaced.

In the longitudinal spaces 19 and 20 at the 25 outer end portion of the blade 1, there are the following indicia: "Figures in these two lines are the number of inches the longest jack rafters are shorter than the common rafters. Arrows point to rise of roof." At intervals 30 in the length of the spaces 19 and 20 and below each of the words "Spacing" in the longitudinal space 18, there appears the word "Rise", an arrow being located opposite each of said words, where it occurs in the length of 35 the spaces 19 and 20, and the rise in inches being indicated by ordinals, as indicated by the numeral 25. In the linear spaces 19 and 20 and opposite the said ordinals which are designated by the numeral 25 and which 40 indicate the rise in inches, there are other numeral designations indicated respectively by the numerals 26 and 27, which represent the number of inches the longest jack rafters are shorter than the common rafters in accordance 45 with the rise in inches. It will be readily seen that if the rafters are spaced twelve inches apart and the rise is eighteen inches the longest jack rafters will be forty-eight and one-fourth inches shorter than the common rafters, whereas if the rise is twenty-four inches, the difference in length between 50 the common rafters and longest jack rafter will be sixty inches.

On the arm of the square and in a line between 55 the linear scales 12 and 14, there are certain numerical designations indicated by the numeral 28 and located substantially at the inch divisions of the scale 12 which range from 5 to 10 inclusive, and at one end of this 60 series of numerical designations there is the legend "Miter cuts from five to ten sided figures," and at the other end of the said series there occurs the legend "Cut on figures to right."

65 Figure 2 of the drawings, illustrates the op-

posite side of the instrument and upon this face of the blade 1 there is provided a linear scale indicated by the numeral 29 and representing inches and fractions of inches, this scale extending from the inner end of the said 70 outer edge of the blade to the outer end of said edge. A similar linear scale 30 is represented upon this face of the blade and represents inches and fractions of inches and extends along the inner edge of the blade from 75 the inner end of the said edge to the outer end thereof. A linear scale 31 is provided along the outer edge of the arm 2 of the square at the face thereof illustrated in Figure 2, and extends from the inner end of said edge to 80 the outer end thereof, and a similar scale 32 is represented upon the said face of the arm along the inner edge thereof and extends from the inner end of said edge to the outer end thereof.

85 Scale lines 33 extend transversely of the blade 1 at the inch divisions of the linear scale 29 and intersect certain longitudinal lines which are represented on this face of the said blade, these lines defining longitudinal spaces 90 indicated by the numerals 34, 35, 36, 37 and 38. In the longitudinal space 34 there are numerical designations 39 occurring at certain of the lines 33, and at the end of this face of the blade and at the end of the series of 95 numerical designations 39, there is the legend "Side cut for hip or valley rafters in this line." A similar series of numerical designations 40 are arranged in the space 35 and at the end of the series there occurs in the 100 said space 35, the legend "Side cuts for hip or valley jack rafters in this line." In the space 36, at intervals, there appears the legend "Spacing" and between the division lines 33 opposite each of these legends, which are 105 indicated by the numeral 41, there appear ordinals indicated by the numeral 42, indicating inches. The word "Rise" indicated by the numerals 43 and 44 appears at intervals in the spaces 37 and 38 respectively and opposite the word "Spacing" 41, wherever the latter word appears, and in the said longitudinal spaces 37 and 38 and opposite each word "Rise" there are numerical designations 45 indicating rise in inches.

110 The space upon the face of the arm 2 shown in Figure 2 of the drawings, and occurring between the linear scales 31 and 32, is divided by a longitudinal line 46 and at one side of this line there are numerical designations 47 and at one end of the series the legend "Difference in length in studding in the gables in this line for 16" spacing." Other numerical designations 48 are located at the opposite side of the said line 46 in a longitudinal series and at one end of the series there occurs the legend "Side cuts in this line."

115 The ordinals indicated by the numeral 42 and occurring in the space 36, indicate the 120

spacing in inches of the common and jack rafters of a roof, the ordinals which immediately follow the word "Rise" wherever this word occurs in the longitudinal spaces 37 and 5 38, indicating the rise in inches of different roofs, per foot, and the numerical designation indicated by the numeral 45 represents the difference in length between the jack rafters and the common rafters, in accordance with the rise in inches to the foot.

The square is employed in laying out common rafters, jack rafters, hip rafters, and valley rafters, and in laying out the various rafters, the length of one of the common 15 rafters is first determined in order that the same may be used as a pattern for laying out all of the jack rafters. In obtaining this result, and assuming that the building dimensions are twenty-four feet by thirty-six 20 feet and that the ridge is twelve feet long and the rise eight inches per foot, the seat cut S and tail cut T are laid out by the use of the square, as shown in Figure 6, the square being disposed upon the piece of lumber which is to constitute the common rafter, with the twelve inch mark of the scale 11 and the eight inch mark of the scale 12 in registration with one longitudinal edge of the said rafter, in the customary manner. Then, by 25 30 laying the square upon the rafter in the position shown in Figure 6 of the drawings, with the said twelve inch and eight inch scale marks in registration with one longitudinal edge of the rafter and moving the square along the 35 rafter in step by step movement a number of steps corresponding to the number of feet equalling one half the width of the building in feet, as shown in Figure 7, and then moving the square back along the 40 rafter a distance equal to one half the thickness of the ridge rafter of the building to be erected, the outer edge of the arm of the square may serve as a guide along which to draw a pencil or other marker to indicate the 45 line on which this end of the rafter is to be cut to complete the layout of the rafter.

Several examples of the use of the square embodying the invention are as follows: Let it be assumed that it is desired to mark a side 50 cut for a hip or valley rafter which is to be disposed at an eight inch rise per foot. Referring to the blade 1 of the square in Figure 2, and to the disconnected end portion of the blade, it will be noted that the indicating 55 numerals for side cuts for hip or valley rafters are to be found in the longitudinal series of spaces 39 and, locating the eight inch mark on the edge of the blade in the scale 29, it will be observed that the numerals 9—10 60 appear directly below the scale mark 8. Therefore, this indicates that the square is to be placed upon the rafter to be cut with the nine inch mark of the scale 31 of the arm 2 and the ten inch mark of the scale 29 of the 65 blade 1 registering with the edge of the rafter

whereupon a pencil or other marker may be drawn along the outer edge of the blade 1. If a jack rafter is to be marked for a side cut with a rise of eight inches per foot, it will be noted that in the longitudinal series of spaces 70 40, in which numerals appear indicating side cuts for hip or valley jack rafters, the numerals 10—12 appear under the eight inch mark of the scale 29 and, therefore, the square will be disposed as before stated with the ten 75 inch mark of the arm 2 and the twelve inch mark of the blade 1 registering with the edge of the rafter. Where an octagon hip rafter is to be marked for a side cut, and the rise is eight inches per foot, reference is had to the side of the square shown in Figure 1 of the drawings and to the numeral designations in the longitudinal series of spaces 16 and it will be observed that under the eight inch linear scale marks of the scale 11, the numerals 80 85 5—15 $\frac{3}{8}$ appear. Therefore, the square is applied with the five inch mark of the arm 2 and the fifteen and three-eighths inch mark of the blade 1 registering with the edge of the rafter and the same is marked as before. If an octagon jack rafter is to be marked for a side cut where the rise is eight inches per foot, reference is made to the scale in the longitudinal series of spaces 17 on the blade 1 of the square, as shown in Figure 1, which scale 90 95 gives indicating numerals for side cuts for octagon jack rafters and it will be observed that under the eight inch mark of the linear scale 11, the numerals 5—14 $\frac{1}{2}$ appear. Therefore, the square is disposed upon the 100 105 octagon jack rafter with the five inch mark of the arm 2 and fourteen and one-half inch mark of the blade 1 registering with the edge of the said rafter, and the rafter may then be marked.

Having thus described the invention, what I claim is:

A framing square having a blade and an arm extending transversely from one end thereof and disposed at right angles thereto, 110 linear scale markings being provided along both faces of the arm and blade and designating inches and fractions thereof, the blade bearing a series of numerals beneath certain of the inch markings on one of its faces and each indicating side cuts for the hip and valley rafters of a roof, the inch rise per foot run of which corresponds to the companion inch marking of the scale, another series of numerals being provided upon the blade beneath certain of the inch markings of the said scale and indicating side cuts for hip and valley jack rafters, the other face of the blade having a series of numerals provided thereon beneath certain of the inch markings of its scale to designate side cuts for octagon rafters of a roof, the inch rise per foot run of which corresponds to the companion inch markings of the scale, another series of numerals being 115 120 125 130 provided thereon beneath certain of the inch

markings of the last-mentioned scale to designate side cuts for octagon jack rafters, the blade further having provided upon its last-mentioned face a plurality of series of numerals indicating the distances rafters are spaced from each other between longitudinal center lines thereof, numerals below the series of numerals indicating various rises in inches

per foot of roofs, and numerals below the series of numerals and opposite the last-mentioned rise indicating numerals designating the number of inches the longest jack rafters are shorter than the common rafters.

In testimony whereof I affix my signature.

CHARLES R. CRANDLEMERE. [L.S.]
